Primary Examiner — David G Muller(74) *Attorney, Agent, or Firm* — Bryan Cave Leighton Paisner LLP**CLAIM**

The ornamental design for an electronic vaporizer base, as shown and described.

DESCRIPTION

FIG. 1 is a front perspective view of our electronic vaporizer base;

FIG. 2 is another front perspective view thereof;

FIG. 3 is a front elevational view thereof;

FIG. 4 is a rear elevational view thereof;

FIG. 5 is an elevational view of the right side thereof;

FIG. 6 is an elevational view of the left side thereof;

FIG. 7 is a top plan view;

FIG. 8 is a bottom plan view;

FIG. 9 is a bottom perspective view thereof; and,

FIG. 10 is another bottom perspective view thereof.

The broken lines immediately adjacent shaded surfaces depict boundaries and form no part of the claim; all other broken lines are for purposes of illustrating portions of the electronic vaporizer base that form no part of the claimed design.
